UNITED STATES PATENT OFFICE.

WILLIAM A. DENNEY, OF QUINCY, ILLINOIS, ASSIGNOR TO J. E. LITTLE METAL WHEEL COMPANY, OF QUINCY, ILLINOIS, A CORPORATION.

MOLDING-MACHINE.

1,111,529.

Specification of Letters Patent.

Patented Sept. 22, 1914.

Application filed March 9, 1914. Serial No. 823,374.

To all whom it may concern:

Be it known that I, WILLIAM A. DENNEY, a citizen of the United States of America, residing at Quincy, in the county of Adams 5 and State of Illinois, have invented certain new and useful Improvements in Molding-Machines, of which the following is a full, clear, and exact description, reference being had to the accompanying drawings, forming 10 part of this specification.

My invention relates to a molding machine and has for its object the production of means for operating patterns to facilitate the work of forming sand molds.

15 The preferred form of my invention comprises a flask support for supporting a flask member, and pattern holders operable to shift pattern sections, so as to properly locate the pattern in the flask member, and to 20 withdraw the pattern from the mold after the ramming operation. The machine preferably includes two pattern holders operable to release the sectional patterns from the mold section without rapping the patterns, 25 one of the pattern sections being moved upwardly from the top of the mold section, while the other pattern section is shifted downwardly from the bottom of the mold section.

30 Figure I is a vertical section of a molding machine embodying the features of my invention. Fig. II is a vertical section of the upper portion of the machine, looking in the direction indicated by the arrow II in 35 Fig. I and showing the pattern sections withdrawn from the mold member. Fig. III is a horizontal section taken on the line III—III, Fig. I. Fig. IV is a perspective view of the separable pattern sections. Fig. 40 V is a perspective view of the upper portion of the lift rod or support for the upper pattern section.

In the accompanying drawings: 1 designates a base surmounted by corner posts 2, 45 and 3 designates a flask support secured to the upper ends of said corner posts. The flask support is formed with a large opening for the reception of a pattern A and a flask member B seated upon the flask support is so positioned that its lower edge overlaps the margin of pattern section A. Upon referring to Fig. I it will be noted that the pattern section A serves as a closure 50 for the bottom of the flask member and that the flat face 4 of said pattern section is flush

with the top face of the flask support 3. The pattern section A is formed with a central boss 5, lugs 6, and core prints 7 radiating from said lugs. If desired, the lower edge of the flask member may be notched, 60 as seen at 8, to receive the core prints 7. In this connection it is to be understood that the invention is not in any way limited to the specific type of pattern I have shown and described.

65 The pattern shown comprises the bottom section A and a top section C adapted to interlock with said bottom section, the bottom pattern section being provided with a central opening 9 adapted to receive a bifurcated stem 10 projecting from the top pattern section. In uniting the pattern sections for the molding operation, lugs 11 extending from a cross-bar secured to the stem 10, are passed through notches 12 in the bottom 70 pattern section (Fig. IV), and the top pattern section is then turned to positively interlock the pattern sections, thereby holding the patterns in their proper relative positions while the sand is rammed in the flask 75 member.

80 The means for supporting and operating the separable pattern sections comprises a vertically movable sleeve 13 having a head 14 at its upper end, said sleeve being slidably mounted in a hollow post 15. The bottom pattern section A is seated on and secured to the head 14. A vertically movable lift rod 16, slidably mounted in the sleeve 13, is provided with a flat upper end 85 which extends into the bifurcated stem 10 on the pattern section C. The lift rod is so fitted to the top pattern section that the lift rod may be operated to turn and lift 90 said pattern section.

95 17 designates a foot lever, in the form of a yoke, pivoted at 18 to the post 15 and provided with a weight 19 at its rear end. Connecting bars 20 connect the foot lever 17 to the vertically movable sleeve 13, and 100 a lift bar 21 is connected at its lower end to said foot lever. The upper end of the lift bar 21 extends through a slot 22 in the sleeve 13 and lies below the lift rod 16.

105 23 designates a pin secured to the lift bar 21 and engaging the sleeve 13 to maintain the free upper end of said lift bar in its proper position.

110 An operating rod 24, secured to the lift rod 16, extends through the L-shaped slot

25 in the sleeve 13, the said operating rod 24 serving as a handle for turning the lift rod 16 as will be hereinafter described.

The parts may be moved to the position seen in Fig. 1 by the weighted foot lever, and the connecting bars 20 and the bottom pattern holder are then forced upwardly by said weighted lever, this upward movement being limited by suitable abutments, for example the head 14 may engage the flask support 3. The connecting bars 20 are pivotally connected to the weighted lever 17 by pivot pins 20^a which may be inserted into any of the holes 20^b in lever 17 to vary the downward movement of the pattern member A. The movement of the pattern member C may be varied by adjusting the lift bar 21, said bar being provided with a series of holes 21^a adapted to receive the pivot pin 21^b.

When the weighted lever 17 occupies the position shown in Fig. I, the lift bar 21 is located in its lowermost position and the two pattern sections which then engage each other may be interlocked with each other by shifting the operating rod 24 in the lower portion of slot 25, thereby turning the lift rod 16 and the upper pattern member C to interlock the lugs 11 with the pattern member A. After the ramming operation, the operating rod 24 is turned in the L-shaped slot 25, so as to turn the lift rod 16, thereby turning the circular upper pattern section about its axis to release it from the sand without rapping the pattern and without injuring the mold. When the lift rod is turned to release the top pattern section, the lugs 11 carried by the bifurcated stem 10 are brought into registration with the notches 12 in the bottom pattern section to unlock the top pattern section from the bottom pattern section and the pattern sections may then be separated from each other. The foot lever 17 is then operated to pull the links 20 downwardly thus withdrawing the bottom pattern section from the lower portion of the mold, at the same time moving the lift bar 21 upwardly with the result of pushing the top pattern section from the mold. The pattern sections are then located in the position shown in Fig. II and the top pattern section C may be readily lifted from the rod 16 to permit the removal of the flask member from the machine.

The lift rod 16 is provided with a guide pin 16^a at its upper end, which guide pin extends into the top pattern member as shown in Fig. I and serves to guide said pattern member while it is being withdrawn from the sand.

The pattern holders are locked in the positions seen in Fig. II by a latch dog 25 pivoted to the foot lever 17 and adapted to interlock with the base 1 when the foot le-

ver is depressed to separate the pattern sections.

The lift rod 16 drops by gravity when the lift bar 21 moves downwardly, and to prevent sand from interfering with such movement by collecting between the lift rod and sleeve 13, the lift rod is provided with longitudinal grooves 26 through which sand may readily drop and pass out through the base 1.

I claim:

1. A molding machine comprising pattern holders for supporting separable pattern sections, a flask support adjacent to said pattern holders, for supporting a flask member within which the pattern sections are supported, means for turning one of the pattern holders to release one of the pattern members, and means for moving said pattern holders in different directions to draw one of the pattern sections from the upper portion of the flask member and to draw the other pattern section from the lower portion of the flask member.

2. A molding machine comprising telescoping pattern holders adapted to support separable pattern sections, a flask support for holding a mold member around the separable pattern sections, means for turning one of the pattern holders to release a pattern section from the mold member, and means for operating said telescoping pattern holders to draw one of the pattern sections from the upper portion of the mold member and to draw the other pattern member from the lower portion of the mold member.

3. A molding machine comprising telescoping pattern holders adapted to support separable pattern sections, a flask support for holding a mold member around the separable pattern sections, means for turning one of the pattern holders to interlock the separable pattern sections with each other, and means for operating said telescoping pattern holders to draw one of the pattern sections from the upper portion of the mold member and to draw the other pattern member from the lower portion of the mold member.

4. A molding machine comprising telescoping pattern holders adapted to support separable pattern sections, a flask support for holding a mold member around the separable pattern sections, an operating device for shifting the pattern holders in opposite directions, and means for locking the operating device to hold the pattern sections away from each other.

5. A molding machine comprising a pattern holder adapted to support a pattern member, a flask support for holding a mold member around said pattern member, means for turning said pattern holder so as to turn the pattern member for the purpose de-

scribed, and means for moving said pattern holder to separate the pattern section from said mold member.

6. A molding machine comprising telescoping pattern holders adapted to support separable pattern sections, a flask support for holding a mold member around the separable pattern sections, means for operating one of said telescoping pattern holders to 10 interlock said pattern sections with each other and to unlock said pattern sections, and means for sliding said pattern holders to draw one of the pattern sections from the upper portion of the mold member and 15 to draw the other pattern member from the lower portion of the mold member.

7. A molding machine comprising a pattern holder adapted to support a circular pattern member, a flask support for holding 20 a mold member around said circular pattern member, and means for turning said pattern holder so as to turn the circular pattern member about its axis for the purpose described.

25 8. A molding machine comprising a rockable pattern holder adapted to hold a circular pattern member, a flask support for

holding a mold member around said circular pattern member, and means for rocking said pattern holder so as to turn the circular pattern member about its axis, thereby releasing said circular pattern member from the mold member. 30

9. A device of the character described comprising pattern sections adapted to interlock with each other to form a sectional pattern, a flask member surrounding said pattern sections, and means for turning one of said pattern sections, to interlock it with the other, when the pattern sections are 35 located in said flask member. 40

10. A molding machine comprising telescoping members one of which constitutes a movable pattern holder, one of said members being provided with longitudinal 45 grooves forming passageways between said telescoping members, a mold member adjacent to an end of said movable pattern holder, and means for operating said movable pattern holder.

WILLIAM A. DENNEY.
